UNITED STATES PATENT OFFICE.

JOHN V. RICE, JR., OF BORDENTOWN, NEW JERSEY, ASSIGNOR TO RICE GAS ENGINE COMPANY, OF BORDENTOWN, NEW JERSEY, A CORPORATION OF NEW JERSEY.

VACUUM IGNITER.

Refiling of application Serial No. 832,510, filed April 17, 1914. This application filed October 20, 1920.
Serial No. 418,301.

To all whom it may concern:

Be it known that I, JOHN V. RICE, Jr., a citizen of the United States, and resident of Bordentown, in the county of Burlington 5 and State of New Jersey, have invented certain new and useful Improvements in Vacuum Igniters, of which the following is a specification, reference being had therein to the accompanying drawing.

10 This invention relates to an igniting device for internal combustion engines, the device being of the general class known as tube igniters which cause combustion of the explosion mixture by means of a hot tube 15 instead of a spark. One of the objects for which I am striving in the present invention is to produce a tube which can be kept heated at all times to a high temperature so that it will be ready to perform whatever duty 20 is required of it, and hence will not become cold and ineffective when as with a light load the explosions are not as frequent as they are when the engine is operating more rapidly with a heavier load. Another object 25 is to construct an igniter of the kind mentioned in an economical and efficient way so that the best results of every kind will be achieved in practice. With these and other various objects in view it will appear 30 throughout the description and claims that my invention consists essentially in the provision of a vacuum or partial vacuum surrounding or contiguous to the igniter tube and the explosion cavity; and also in means 35 for creating such a partial vacuum and in a chamber wherein it is produced; and furthermore the invention may be said to reside in numerous details and peculiarities in the construction, arrangement and combination 40 of the various parts, substantially as will be hereinafter more fully described and claimed.

In the accompanying drawing illustrating my invention:

45 Figure 1 is a vertical section of an igniting device constructed in accordance with my present invention and shown as practically applied for use with an internal combustion engine cylinder.

50 Figure 2 is a similar sectional view of a modification of the invention.

Like characters of reference designate corresponding parts throughout the different figures of the drawing.

1 denotes the cylinder of an engine; 2 its 55 water jacket; 3 a piston in the cylinder. At the end of the cylinder is a head 6 having an explosion cavity 6^a therein. Water is introduced into the water jacket 2 through the pipe 11. The fuel, consisting of any suitable heavy oil, is supplied through the pipe 4 having the injector nozzle 5 which sprays in the oil, it being immediately converted into gas in the chamber 6^a and then exploded by the igniting device, the operation being, 60 so far as the explosion is concerned, similar to that of a Diesel engine. It will be understood, of course, that when the piston reaches the top of the compression stroke, the small injector 5 opens and a charge of liquid fuel 70 and compressed air is blown into the already red hot cylinder and that after the valve closes, the hot gases expand during a portion of the travel of the piston, after which the exhaust valve opens and relieves 75 the pressure, but I do not consider it necessary to illustrate in detail the operation of any of the well known principles of an engine of this type, since my invention is concerned with the igniter device. 80

Communicating with the cylinder head 6 through the passage 12, is a chamber 13 containing the metallic tube igniter 14. Tube 14 is supported in a casing having an outer wall 7 and an inner wall 10, the latter being 85 preferably corrugated and there being between the two walls 7 and 10 a space 8 in which a greater or less vacuum is created by a vacuum pump which sucks air through the pipe 9 connected with the space 8. Thus I 90 surround the tube 14 by a vacuum or partial vacuum for the purpose of enabling the heat to be kept in the igniter tube so that it will be ready for efficient service at all times. Tube 14 is heated from without by means of 95 a torch, or in any other suitable way, and if desired its outer open end may be covered, although this is not necessary. The corrugated character of the inner wall 10 of the vacuum chamber 8 gives to said wall more 100 or less flexibility and enables it to serve more efficiently in performing its work. When once the engine has been set in operation and the explosions of the ignited fuel are taking place with rapidity, the igniter tube 14 will become very hot. It is desirable to keep it so because the load fluctuates and if the igniter should become cooled or

comparatively so when the load is quite light, the result will be that it might fail to operate when a heavy load is thrown on. The use of the vacuum, however, causes the igniter to retain the heat and enables it to be ready for the best work under all conditions. The degree of vacuum in the chamber 8 will vary and, of course, can be regulated by the operation of the vacuum pump 19 so as to be kept at any predetermined degree.

It may be that in the operation of a vacuum igniter of this kind which keeps hot in accordance with the thermos principle, a too high temperature may be reached and kept 15 for a time, one that would be dangerous or disastrous to the mechanism, and, hence, it is desirable to provide a means for preventing this. This I do by furnishing a device which will automatically operate to partially 20 destroy the vacuum by letting air into the chamber 8 at a time that this excessive temperature has been reached. Such a device I designate a thermostat. It is shown in section in Figure 1 on the side wall 7 of 25 the tube casing. It consists of a horizontal casing 15 screwed into the outer wall 7 of the tube chamber and containing a suitable valve 16 having a stem 17 which passes through the casing 15 in a loose way and 30 has its inner end in contact with the flexible corrugated wall 10. A spring 18 is interposed between the valve 16 and the opposite end of the casing 15, which consists of a perforated plug 19 screwed into the end 35 of the casing 15. It will be obvious, therefore, that as the pressure in the chamber increases in consequence of the operation of the engine and the high degree of temperature of the combustion mixture and of the 40 tube igniter 14, said pressure against the corrugated wall 10 will move the stem 17 of the valve 16 sufficiently to unseat said valve from its seat 20 and allow air to flow in through the perforated plug 19, past the 45 valve 16, and through the casing 15 into the vacuum space 8, and thus partially destroy the vacuum. A slight cooling, however, will restore the position of the parts, and the stem 18 will close the valve 16 again against its seat 20. The use of a thermostat of this 50 kind is a valuable adjunct to an igniting device operating in connection with a vacuum for keeping it at a high temperature.

Referring to Figure 2, it will be seen that 55 I have shown a modification in the arrangement of the parts, though the principle is the same and the general construction is on the same lines. In this view I have shown a part of the cylinder 1, water jacket 2, and 60 piston 3. At the end of the cylinder 1 is the head 21 entered by the fuel supplying device 22 having injector nozzle or needle valve 23. At the center of the head 21 is a spherical, globular or ball-shaped compartment 24, being preferably ribbed as at 65

Said spherical chamber 24 is surrounded almost entirely, except at the top and bottom where it is supported, by a chamber 26, which I term a vacuum chamber, because from said chamber 26 the air has been 70 practically excluded by being withdrawn through the outlet pipe 27 by a vacuum pump placed at any suitable point and not shown. At the top of the chamber 24, entrance is had thereto through a central passage 28 which communicates with the tube igniter 29 located centrally within a removable cover 30 which may be dispensed with if desired, said cover having a door 31 adapted to be opened for the purpose of introducing a torch or other means for primarily heating the tube 29 prior to the beginning of the cycle of operations of the gas engine.

In the operation of the modification represented in Figure 2, it will be evident that the fuel introduced through the injector 23 and flashed into gas in the chamber 24 will be ignited as soon as it comes into contact with the tube 29, which has previously been 90 heated red hot. In order to guard against any undue rise in the temperature of the engine, I find it desirable to use with this modification of the engine the same thermostat construction as in the case of the mechanism illustrated in Figure 1, the stem 17 in this case bearing against the spherical wall of the chamber 24. The operation of the device in Figure 2 is, however, quite similar in all respects to that of the construction shown in Figure 1, except in so far as there are slight differences owing to changes in the structure and arrangement of the different parts.

It will be obvious that my invention resides primarily in the discovery that a vacuum surrounding a tube igniter in an engine of the Diesel or similar type enables the igniter to be kept hot at all times, whatever may be the load or duty that is being 110 performed by the engine, and, hence, no risk is run in the use of an igniter so protected that the engine will stop or run unevenly, but with a highly heated igniter tube whose temperature does not vary, it will be evident 115 that many extremely useful results will be attained. Such being the broad idea, it is obvious that it may be embodied in mechanical forms varying widely in their contour and the combination of the various details, 120 and I therefore claim the liberty of so applying the vacuum principle to any mechanical structure as will enable the igniter to be successfully employed in any kind of an internal combustion engine by keeping the 125 temperature of the tube at such degree as may be found desirable and useful, and I, therefore, reserve the liberty of modifying the structure and employing its forms within 130 very wide limits for the carrying out of the

essential underlying principles of the invention. Although I have herein referred to the igniter as a "tube" igniter, yet it is obvious that it may partake of other forms 5 and may be a bulb if desired, or in its tubular form it may be described as a bulb; furthermore a collar may be employed that may act as a resisting power intermediate between the corrugated wall and the thermostatic valve, for it will be observed that in 10 some cases the thermostat valve stem may lie directly against the corrugated wall, and in other cases may be differently arranged and supported, the principle of action being in 15 both cases practically the same as the pyrometer acts when the heat is too great.

Having thus described my invention, what I claim as new and desire to secure by Letters Patent, is:—

20 1. In an igniter for internal combustion engines, the combination with a tube igniting device, of means for keeping it at a high temperature after it is once heated, said

means comprising means for applying a vacuum to said igniting device to prevent 25 the radiation of the heat, and a thermostat device for preventing any undue rise of temperature in the igniter tube.

2. In an igniter for internal combustion engines, the combination of a tube device, a 30 chamber adjacent thereto, the inner wall of said chamber being corrugated, a space contiguous to the corrugated wall, from which space the air has been substantially withdrawn to create a partial vacuum, all substantially as described.

3. The combination with a tube igniter, of a chamber wherein the inflammable mixture is compressed for ignition, the inner wall of said chamber being corrugated, and 40 means for creating a partial vacuum on the opposite side of said wall so as to prevent heat radiation.

In testimony whereof I hereunto affix my signature.

JOHN V. RICE, JR.
